UNITED STATES PATENT OFFICE.

CHARLES H. HOWARD, OF SAUGUS, MASSACHUSETTS, ASSIGNOR, BY MESNE ASSIGNMENTS, TO AMERICAN RE-ENFORCED PAPER COMPANY, OF ATTLEBORO, MASSACHUSETTS, A CORPORATION OF MASSACHUSETTS.

SEALING DEVICE.

Application filed October 26, 1925. Serial No. 64,779.

This invention relates to devices for sealing or securing together the overlapping edges of a tube or container, and more particularly to a device for applying a water-proof adhesive to the parts to be sealed.

Various means have been provided heretofore for applying pastes and water soluble adhesives to the portions of a sheet of paper to be sealed, but the adhesive applying devices proposed heretofore are not suitable for applying a water-proof adhesive of the type that solidifies as it becomes cool and therefore must be applied in a hot condition.

If an adhesive of the type that remains soft and viscous only while in a hot condition is employed to secure the portions of a paper tube or container together, it is found difficult to produce strong seams or joints, due to the fact that the hot adhesive when applied to the paper in a thin layer cools so quickly that it becomes more or less stiff and non-viscous before a second piece of paper can be forced into engagement therewith.

One important feature of the present invention therefore resides in means for applying hot waterproof adhesive to a sheet of paper in a thin layer, and in means for quickly forcing a second piece of paper into intimate engagement with the adhesive layer before it has had a chance to cool. This causes the waterproof adhesive to firmly secure the pieces of paper together.

The means of the present invention for applying water-proof adhesive to form strong durable seams or joints may be employed for various purposes, but it is particularly well adapted for use in the manufacture of water-proof bags or containers made of water-proof paper. Because if the joints or seams of these containers are strongly secured together by a water-proof adhesive they will not be affected by moisture, whereas if a water soluble adhesive is employed in making such joints, as heretofore, the seams will give way when exposed to moisture.

A more specific feature of the invention resides in means for depositing a narrow stream of hot adhesive upon a piece of

paper, and in a heated spreader for spreading the adhesive out upon the paper into a thin layer or strip to which a second piece of paper is quickly applied.

Another feature of the invention resides in means constructed to extend inwardly between overlapping portions of a tube or container and adapted to apply hot water-proof adhesive between the overlapping portions to secure them together.

Still another feature of the invention resides in paper feeding means for advancing a sheet of paper having its opposite sides folded into overlapping relation, and which means is so constructed that it pulls the folded sheet forward without pressing on the sheet at the line of fold.

Other features of the invention and novel combination of parts in addition to the above will be hereinafter described in connection with the accompanying drawings which illustrate one good, practical form of the invention.

In the drawings,—

Fig. 1 is a perspective view of a machine provided with means for advancing a sheet of paper and for folding the opposite sides of the sheet into overlapping relation, and is provided with means for depositing adhesive between the overlapping portions of the sheet.

Fig. 2 is a longitudinal sectional view thru the machine of Fig. 1.

Fig. 3 is a perspective view showing the overlapping portions of the sheet of paper with the adhesive applying means projecting between the overlapping portions.

Fig. 4 on an enlarged scale is a vertical sectional view thru the adhesive supply pipe.

Fig. 5 is a perspective view of a portion of a tube showing the overlapping portions adhesively secured together and showing the upper overlapping portion rolled back to disclose the adhesive.

Fig. 6 is a transverse sectional view of the tube shown in Fig. 5; and

Fig. 7 is a sectional view taken on the line 7-7 of Fig. 4.

In the embodiment of the invention shown, the sheet of paper to which the adhesive is to be applied is shown as supported by a table 10. The sheet of paper 11 may be drawn from a supply roll or other source of supply, not shown, and as it passes along the upper face of the table 10 the opposite sides of the sheet are folded inwardly into overlapping relation by the spaced guides or 60 folders 12 and 13, which folders are secured to the upper face of the table in the desired position of adjustment by bolts 14 extending thru elongated slots 15 formed in the arms 16 of the folders. The guide or folder 12 70 serves to fold the side portion 17 of the sheet of paper over the opposite side portion 18, and the sheet of paper thus folded may be advanced over the face of the table 10 by any suitable means.

20 The means shown for advancing the paper lengthwise of the table consists of the feed rolls 19, 20 and 21, mounted upon and rigidly secured to the driving shaft 22. The ends of this shaft are journaled in the bearings 23 and 24 supported at the opposite sides of the table 10, and the shaft 22 may be driven by the pulley 25. These feed rolls are supported above the sheet of paper, and below the sheet of paper are yieldingly 80 mounted the cooperating rolls 26, 27 and 28. Various means might be provided for urging these yielding rolls towards the cooperating rolls 19, 20 and 21 so that they will frictionally engage the sheet of paper, and 90 30 in the construction shown the yielding rolls 26, 27 and 28 are supported by the levers 29, 30 and 31 respectively. The rear end of each of these levers is secured to a shaft 32 supported in a fixed position below the table 40, and the free ends of these levers are urged upwardly by springs 33, 34 and 35, the upper ends of which rest against the levers, and the lower ends of these springs rest upon the transversely extending bar 36. 100 40 Each of the levers just mentioned consists of a pair of spaced bars between which the respective rollers are mounted and these rollers are rotatably secured to the levers by the short shafts 37. The arrangement is 50 such that the upward pressure of the springs upon the outer ends of the levers forces the rollers 26, 27 and 28 upwardly into frictional engagement with the paper passing between the upper and lower rolls, 60 to cause the power driven rolls to advance the paper.

It is important that the means provided for advancing the sheet of paper 11 over the face of the table shall not press upon the 70 sheet 10 at the line of fold along the opposite sides of the sheet of paper, which line is indicated by 38 and 39. If a substantial pressure is exerted upon the paper at the line of fold it will crease the same and will 80 materially reduce the strength of the paper.

where it is folded. The distance between the upper feed rolls 19 and 21, in the construction shown, is therefore less than the width of the sheet of paper advanced by these rolls, and the same is true of the lower feed rolls 26 and 28. As a result the co-operating rolls serve to advance the sheet of paper without pressing upon the sheet at the lines of fold, indicated by 38 and 39.

As stated an important feature of the present invention resides in the means for applying water proof adhesive to a sheet of paper to secure together portions thereof, and in the construction shown the water proof adhesive such as black asphaltum is 75 contained within the receptacle 40, which may have any desired configuration, and the lower portion of this receptacle is preferably somewhat cone-shaped, as shown at 80 41. This receptacle may be supported in spaced relation to the table 10 by any suitable means such as the downwardly extending bolts 42 the lower ends of which are adjustably connected by nuts 43 to lugs 44 projecting laterally from the opposite sides 90 of the receptacle 40.

When the water proof adhesive is used to unite the overlapping side portions of a sheet of paper, as in the present case, it is desirable to provide the adhesive receptacle 95 40 with a laterally extending pipe or other means which is adapted to extend inwardly between the overlapping portions 17 and 18 of the sheet of paper. The receptacle 40 is therefore shown as having a curved pipe or 100 elbow 45 leading from the lower portion of the receptacle, and this elbow is provided with a threaded outer end 46 adapted to receive the horizontally extending pipe 47 the outer end of which extends between the 105 overlapping portions of the sheet of paper.

The end of the pipe 47 may be closed with a plug 48 and this pipe is provided near its outer end with a small hole or port 49 thru which the adhesive may issue in the form of a stream 50, as best shown in Figure 4. It is desirable to provide valve means for controlling the discharge of adhesive thru the port 49 and to this end, in the construction shown, a tube 51 is rotatably mounted within the pipe 47 and this tube is provided with a port 52 which may be rotated either into or out of alignment with the port 49. The inner tube 51 may be operated by a handle 53, the inner end of which may be 110 screwed into a wall of the tube, and this lever extends thru a slot formed in the outer pipe 47, and which slot limits the angle thru which the inner tube 51 may be rotated.

It is important to provide means for 115 keeping the adhesive within the receptacle 40 and pipe 47 at a relatively high temperature, and to this end, in the construction shown, an electric heating coil 54 is provided within the receptacle 40 and the lower 120 125 130

end portion of this coil preferably extends lengthwise within the pipe 47, as indicated by 55.

If desired, the conductor wires 56 of the heating coil may be mounted within a tube 57 which protects the wires from the adhesive. It is desirable to prevent the loss of heat from the receptacle 40 and the laterally extending pipe 47; the pipe 47 is therefore shown as provided with an insulating casing or covering 58, and the receptacle 40 may be likewise provided with an insulating casing.

As a result of the construction just described, it will be seen that as the folded sheet of paper 11 is fed lengthwise of the table the hot water-proof adhesive such as asphaltum will be deposited upon the portion 18 of the sheet of paper in the form 20 of a narrow stream 50. In order to insure the formation of a tight joint between the overlapping portions of the sheet of paper it is necessary to convert the narrow stream 50 of adhesive into a thin layer or strip, 25 as indicated by 59, and to this end, in the construction shown, the pipe 47 is provided at its under face with a spreader 60 which may constitute an enlarged portion formed upon the pipe, and the length of the 30 spreader 60 may serve to accurately determine the width of the adhesive strip 59, since, if the amount of hot adhesive delivered to the paper is properly regulated by adjusting the valve above mentioned, the spreader 60 will flatten the adhesive out into a thin ribbon or strip having a width corresponding to the length of the spreader.

It is important to note that since the pipe 47 is maintained at a relatively high temperature by the electric coil 55 therein the spreader 60 will likewise be maintained at a relatively high temperature with the result that it will serve to flatten the stream of adhesive out into the form of a ribbon or strip without permitting the same to cool appreciably. The upper overlapping portion 17 of the sheet of paper may then be quickly forced into firm engagement with the hot adhesive strip 59 by the cooperating rolls 20 and 27 to effect an intimate engagement of the strip of adhesive with both portions of the sheet of paper before the adhesive has had an opportunity to cool appreciably. This is accomplished, in the present invention, by advancing the sheet of paper 11 over the table at a relatively high speed and by constructing the adhesive supply pipe 47 so that it will extend inwardly between the overlapping portions of the sheet while 50 at the same time it spreads the overlapping portions to only a slight degree. As a result of this construction the adhesive depositing pipe 47 may be positioned relatively close to the cooperating rolls 20 and 27 which

force the overlapping sheets into intimate 65 engagement with the adhesive.

From the foregoing description and drawings it will be seen that the adhesive applying means described serves to deposit a hot strip or ribbon of a waterproof adhesive 70 between the overlapping portions of a traveling sheet of paper so that the overlapping portions of the sheet may be forced into intimate engagement with the adhesive before the same has cooled sufficiently to reduce its 75 sticky or viscous condition, and as a result a strong joint or seam is formed which is not affected by moisture.

Altho the adhesive applying means of the present invention may be used in various 80 fields for applying a ribbon or strip of water-proof adhesive to a sheet of paper or other fabric, it is particularly well adapted for use in the manufacture of water-proof paper bags. In this case the sheet of paper 85 11 fed to the machine will be a water-proof paper, and the resulting tube shown in Figs. 5 and 6 with the overlapping edges strongly secured together may be severed transversely at intervals to produce short tubes 90 which may be formed into water-proof bags or containers by closing one end thereof.

What is claimed is:—

1. A device for applying a sealing strip of hot asphaltum to one of the overlapping portions of a sheet of paper to unite the portions while the adhesive is hot, comprising in combination, an adhesive-containing receptacle provided with a pipe-like projection constructed to extend between the overlapping portions of the sheet of paper and provided with an aperture for discharging a narrow stream of adhesive upon the lower of the overlapping portions, a narrow spreader provided upon said projection and having a width corresponding to and adapted to accurately determine the width of the adhesive strip applied to the paper and positioned to spread the adhesive out upon the paper with a smooth ironing action, and means for heating the pipe-like projection and spreader to insure application of the asphaltum to the paper in a hot condition and to spread the adhesive out with a hot ironing action that prevents the adhesive from being chilled by its contact with the paper. 110

2. A device for applying a sealing strip of adhesive in a hot condition between the overlapping portions of a sheet of paper to unite the portions while the adhesive is hot, comprising in combination, an adhesive containing receptacle provided with a pipe-like projection constructed to extend between the overlapping portions of the sheet of paper and having an aperture for discharging a narrow stream of adhesive upon one of said portions, a narrow spreader upon 120 125

said projection and adapted to spread the adhesive out upon the paper with a smooth ironing action into a strip having a width that is accurately determined by the width of

3 the spreader, and means for heating the pipe-like projection and spreader to insure application of the adhesive to the paper in

a hot condition and to spread the adhesive out with a hot ironing action that prevents the adhesive from being chilled by its contact with the paper. 10

In testimony whereof, I have signed my name to this specification.

CHARLES H. HOWARD.
